Attorney:

UNITED STATES PATENT OFFICE.

JOHN N. STOKES, OF BENTONVILLE, ARKANSAS.

EXTENSIBLE STEP FOR RAILWAY-COACHES.

1,187,021.

Specification of Letters Patent. Patented June 13, 1916.

Application filed January 10, 1916. Serial No. 71,281.

To all whom it may concern:

Be it known that I, JOHN N. STOKES, a citizen of the United States, residing at Bentonville, in the county of Benton and State of Arkansas, have invented certain new and useful Improvements in Extensible Steps for Railway-Coaches, of which the following is a specification, reference being had to the accompanying drawings.

10 This invention relates to extensible steps for railway coaches and has for its primary object to provide simple and positively operating means for simultaneously actuating the extensible step and a trap door set 15 in the floor of the coach vestibule over the steps.

It is another and more particular object of the invention to provide an extensible step slidably mounted beneath the series of 20 stationary steps, a hinged trap door, a rock shaft, and relatively movable connections between the rock shaft, the extensible step and the trap door whereby the trap door is lifted to its open position and the step simultaneously extended when the rock shaft 25 is actuated.

It is a further general object of the invention to produce a device of the above character which consists of comparatively few parts which are all of simple form and durable in construction, said device being applicable to the ordinary railway coach at minimum cost and without necessitating extensive alterations in the coach construction.

With the above and other objects in view, my invention consists in the novel features of construction, combination and arrangement of parts to be hereinafter more fully described, claimed and illustrated in the accompanying drawing, in which,

Figure 1 is a fragmentary end elevation, partly in section, of a railway coach, showing my invention applied thereto, the trap door being in open position and the auxiliary step extended; Fig. 2 is a front elevation, the stationary steps being shown in dotted lines and the auxiliary step in extended position; and Fig. 3 is a similar view showing the trap door in its lower closed position and the auxiliary step in an inoperative position.

Referring in detail to the drawing, 5 indicates the vestibule platform of a railway coach and 6 the stationary series of steps leading thereto which are secured to depending side walls 7.

To each of the side walls 7 beneath the series of stationary steps, spaced parallel angle bars 8 are secured, which provide guide ways 9 for the opposite edges of the 60 obliquely disposed body plate 10 of an extensible auxiliary step. At the lower end of this oblique body plate, the step is provided with a horizontally extending tread portion 11. To the under side of the extensible step, centrally thereof, spaced longitudinally extending angle bars 12 are secured.

13 designates a rock shaft which is mounted in suitable bearings 14 beneath the 70 vestibule platform 5 on the upper ends of the series of stationary steps 6. This platform is provided upon one end with a crank handle 15 extending upwardly through the platform 5 and at its other end with a 75 downwardly extending crank arm 16. A rod 17 is connected at one of its ends to this crank arm and has at its other end arranged between the upper ends of the spaced angle bars 12 on the extensible step and pivotally 80 connected thereto, as indicated at 18. A bell crank lever 19 is fulcrumed upon a bolt 20 suitably fixed in one of the supporting beams for the platform 5. To one arm of this bell crank lever, the upper end of a 85 rod 21 is loosely connected, the lower end of said rod being pivotally mounted, as at 22, between the angle bars 12 adjacent to the tread 11 of the extensible step.

In the vestibule platform 5, immediately 90 above the stationary step 6, a trap door 23 is hinged, as at 24, and adapted to close an opening in the platform. An angularly disposed arm 25 is fixed to one of the longitudinal edges of the platform and projects 95 beyond the hinged end thereof. To the extremity of said arm, one end of a rod 26 is loosely connected, the other end of said arm being pivotally connected to the other arm of the bell crank lever 19. The rear vertical wall of the upper stationary step is slotted or cut away to accommodate the rod 26 and the side wall 7 is also cut away so that this rod and the arm 25 may move therethrough when the door 23 is lowered to its 105 closed position as shown in Fig. 3.

In the operation of the device, assuming that the trap door 23 is in its vertical open position and the auxiliary step extended as shown in Figs. 1 and 2 of the drawing, 110 when it is desired to close the trap door and withdraw the step, the operator pulls up-

wardly or raises the crank handle 15, thereby 5 rocking the shaft 13. The crank arm 16 of said shaft exerts an upward pull through the rod 17 on the auxiliary step and slides the same upwardly upon the guide channels 9 so that the tread 11 of the step will be disposed below the lower stationary step 6. The rod 21 being connected to one arm of the bell crank lever 19, actuates said lever, 10 and the rod 26 connected to the other lever arm forces the obliquely disposed arm 25 laterally and lowers the trap door 23 to its closed position within the opening in the vestibule platform 5. A reversal of the 15 above operation, or a downward movement of the crank handle 15, will operate to raise the platform and extend the auxiliary step. Thus, it will be seen that I have provided a very simple and positively acting mechanism 20 for simultaneously moving the auxiliary step to its operative or inoperative position and raising or lowering the trap door above the stationary series of steps. As there are no springs or other easily breakable parts employed in the construction of 25 the device, it will be appreciated that the same will be extremely durable in practical use. The invention can also be readily applied to the ordinary railway coach at nominal cost and without necessitating any material alterations in the construction thereof. 30

While I have shown and described the preferred construction and arrangement of the several elements, it is to be understood 35 that the same are susceptible of considerable modification and I, therefore, reserve the privilege of adopting all such legitimate changes as may be fairly embodied within the spirit and scope of the invention as 40 claimed.

Having thus fully described my invention, what I desire to claim and secure by Letters Patent is:—

1. The combination with a stationary car 45 step, of an extensible auxiliary step mounted beneath said stationary step, a trap door above the stationary step, means connecting the trap door and step for movement in unison including a pivoted element, a single rod 50 connection between the auxiliary step and the trap door respectively and said element, a manually operable rock shaft, and a connecting element between said shaft and the auxiliary step to move the same to its operative or inoperative positions and through 55 said first named means simultaneously raise or lower the trap door.

2. The combination with a stationary car step, of an extensible auxiliary step mounted

beneath said stationary step, a trap door 60 above the stationary step, means connecting the trap door and step for movement in unison including a pivoted element, a single rod connection between the auxiliary step and the trap door respectively and said element, a manually operable rock shaft having a crank on one end, and a rod connecting 65 said crank to the auxiliary step at a point in spaced relation with respect to the point of connection of the first named rod to said 70 step, whereby said step is moved to its operative or inoperative position when the rock shaft is actuated and the trap door simultaneously raised or lowered.

3. The combination with a series of stationary car steps, of an extensible auxiliary step mounted beneath said stationary steps, a hinged trap door arranged above the stationary steps, a bell crank lever, means operatively connecting the respective arms of 80 the bell crank lever to the auxiliary step and the trap door, and manually operable means connected to said step to move the same to its operative or inoperative positions and simultaneously raise or lower the 85 trap door.

4. The combination with a series of stationary car steps, of an extensible auxiliary step mounted beneath said stationary steps, a hinged trap door arranged above the stationary steps, a bell crank lever, means operatively connecting the respective arms of 90 the bell crank lever to the auxiliary step and the trap door, a rock shaft, and means operatively connecting the rock shaft to the 95 auxiliary step to move the same to its operative or inoperative position and simultaneously raise or lower the trap door.

5. The combination with a series of stationary car steps, of an extensible auxiliary 100 step mounted beneath said stationary steps, a hinged trap door arranged above the stationary steps, a bell crank lever, means operatively connecting the respective arms of the bell crank lever to the auxiliary step and the trap door, a rock shaft having an operating handle on one end and a crank on its other end, and a rod connecting said crank 105 to the auxiliary step to move the same to its operative or inoperative positions and simultaneously raise or lower the trap door. 110

In testimony whereof I hereunto affix my signature in the presence of two witnesses.

JOHN N. STOKES.
